UNITED STATES PATENT OFFICE.

CLARENCE E. BONNER, OF CHERRYPOINT, ILLINOIS.

WRENCH.

SPECIFICATION forming part of Letters Patent No. 737,199, dated August 25, 1903.

Application filed May 5, 1903. Serial No. 155,712. (No model.)

To all whom it may concern:

Be it known that I, CLARENCE E. BONNER, a citizen of the United States, residing at Cherrypoint, in the county of Edgar and State 5 of Illinois, have invented certain new and useful Improvements in Wrenches, of which the following is a specification.

This invention has special reference to improvements in pipe-wrenches; and the object 10 of the invention is to provide a strong, cheaply-constructed as to cost, and simple wrench which may be easily and quickly adjusted and which will not grip the pipe under heavy strain so as to crush the pipe.

15 The principal object of this invention is to provide a compact and convenient means for adjusting a movable jaw of the wrench.

I accomplish the objects by the mechanism illustrated in the accompanying drawings, in 20 which—

Figure 1 is a side view of my complete wrench; Fig. 2, a view of the back of the wrench; Fig. 3, a front view with the lower portion of the handle removed, and Fig. 4 a 25 detail of the head of the wrench in partial section.

Like characters of reference indicate like parts throughout the several views of the drawings.

30 In the drawings, 5 is a stationary jaw, and 6 the shank of said jaw, which is of any desired length to form a handle which will afford the required leverage for operating the wrench. The jaw is serrated, as shown at 7, 35 and the shank is provided with the teeth 8.

9 is a holder, open at its edge toward the front of the wrench, in which the wrench-shank is located. It has arm extensions 10^a, which are connected by a loop 10, having an 40 inside socket, as shown in Fig. 4.

11 is an adjustable jaw, having lateral pins 12, by which the jaw is pivotally secured to the sides of the holder 9, the said jaw being placed between said sides, with the pins 12 45 taking into suitable openings therein, as shown. The jaw 11 also has the lateral pins 13, which are inserted in slots 14, formed in the sides of the holder. The end of jaw 11 next to jaw 5 is serrated at 15, and its edge 50 adjacent to the shank 6, at the lower end of the jaw, is provided with teeth 16, which are adapted to engage the teeth 8 of the shank by

the action of a spring 17, seated in the socket in loop 10. A shoe 18 will be interposed between the inner end of the spring 17 and shank 55 6. This shoe has a post 19, which takes into the socket in loop 10 to prevent the displacement of the shoe, and the post has a socket in which the spring 17 is seated, as clearly shown in Fig. 4. By pressing on the outer 60 face of the loop 10, as with the thumb or finger of the person using the wrench, the spring 17 will be compressed, and the holder, of which the loop is an integral portion, will be moved so as to carry the toothed end of jaw 11 out 65 of engagement with the teeth 8 of shank 6. Then the jaw 11 is free to be moved on shank 6 away from the head or jaw 5 the required distance to enable the pipe to be operated on to be introduced between the jaws. When 70 the loop 10 is released, the spring 17 forces the loop out, thereby moving the teeth of jaw 11 into engagement with the teeth 8 of shank 6. The oblique sides of the teeth 8 being toward the jaw 5, permit of the movement of jaw 75 11 toward jaw 5 by simple pressure in that direction against the holder 9.

20 is a stop to limit the outward movement of jaw 5 and its holder on shank 6.

The adjustable jaw 11 has a spring 21, here 8c shown as a spiral spring, but which might be a flat spring, interposed between said jaw and the shank 6 to press the jaw normally away from said shank.

Having thus fully described my invention, 85 what I claim as new, and wish to secure by Letters Patent, is—

1. The combination with a toothed shank having a stationary jaw, of a holder, a movable jaw pivoted to the holder and having 90 teeth opposite the pivot to engage the teeth of the shank, said movable jaw also having pins which enter slots in the holder, a spring between the shank and the movable jaw, a spring on the opposite edge of the shank from 95 the movable jaw between said shank and the holder to move the holder so the teeth of said movable jaw are brought into engagement with the teeth of the shank.

2. The combination with a toothed shank 100 having a stationary jaw, of a holder, a movable jaw pivoted to the holder and having teeth opposite the pivot to engage the teeth of the shank, said movable jaw also having

pins which enter slots in the holder, a spring between the shank and the movable jaw, a spring on the opposite edge of the shank from said movable jaw bearing against the holder 5 to move the latter into engagement with the teeth of the shank, and a shoe between the spring and the shank.

3. The combination with a toothed shank having a stationary jaw, of a holder having 10 an outer extension or loop, said loop having an inside socket, a movable jaw pivoted to and within the holder having teeth opposite the pivot to engage the teeth of the shank, said movable jaw also having pins which

enter slots in the holder, a spring between the 15 shank and the movable jaw, a shoe bearing against said shank and having a post taking in the socket of the holder-loop, said post having a socket and a spring seated in the socket of the post and bearing against the loop. 20

In witness whereof I have hereunto set my hand and seal, at Indianapolis, Indiana, this 30th day of March, A. D. 1903.

CLARENCE E. BONNER. [L. S.]
